(57) **CLAIM**

I claim the ornamental design for a produce clamshell, as
shown and described.

DESCRIPTION

FIG. 1 is a top plan view of the first embodiment of the
produce clamshell;

FIG. 2 is a left side elevational view according to the first
embodiment of the produce clamshell;

FIG. 3 is a bottom plan view according to the first embodiment
of the produce clamshell;

FIG. 4 is a right side elevational view according to the first
embodiment of the produce clamshell;

FIG. 5 is a front elevational view according to the first
embodiment of the produce clamshell;

FIG. 6 is a back elevational view according to the first
embodiment of the produce clamshell;

FIG. 7 is a top plan view of the second embodiment of the
produce clamshell;

FIG. 8 is a left side elevational view, according to the second
embodiment of the produce clamshell;

FIG. 9 is a bottom plan view according to the second
embodiment of the produce clamshell;

FIG. 10 is a right side elevational view according to the
second embodiment of the produce clamshell;

FIG. 11 is a front elevational view according to the second
embodiment of the produce clamshell; and,

FIG. 12 is a back elevational view according to the second
embodiment of the produce clamshell.
